UNITED STATES PATENT OFFICE

2,322,020

COMMUTATOR

Lawrence F. Hemphill, Fort Wayne, Ind., assignor
to General Electric Company, a corporation of
New York

Application October 6, 1942, Serial No. 460,937

7 Claims. (Cl. 171—321)

My invention relates to commutators for dynamo-electric machines.

An object of my invention is to provide improved and simplified commutator constructions.

Further objects and advantages of my invention will become apparent and my invention will be better understood from the following description referring to the accompanying drawing, and the features of novelty which characterize my invention will be pointed out with particularity in the claims annexed to and forming part of this specification.

In the drawing, Fig. 1 is a side elevational view, partly broken away, illustrating an embodiment of my invention; Fig. 2 is an end view, partly broken away, of the commutator shown in Fig. 1; Fig. 3 is a perspective view of the clamping ring shown in Figs. 1 and 2; Fig. 4 is a perspective view of the insulating support shown in Figs. 1 and 2; and Fig. 5 is a side elevational view of a commutator segment such as that shown in Figs. 1 and 2.

Referring to the drawing, I have shown in Figs. 1 to 5 a simplified commutator construction comprising a plurality of commutator segments formed of two sections 10 and 11. These commutator bars are mounted on an insulating sleeve support 12 mounted on a shaft 13. The sleeve is provided with an insulating supporting shoulder element 14 extending outwardly at an angle to the sleeve, and a plurality of circumferentially spaced apart grooves 15 is formed in the axially extending sleeve portion 12 and shoulder 14. The commutator segments are formed prior to assembly, as shown in solid lines in Fig. 5, with the portions 11 extending outwardly at an angle 16 to the portions 10 greater than the angle of the shoulder 14 relative to the sleeve 12; that is, the angle 16 between the commutator segment portions 10 and 11 is greater than the angle 17 between the portions of the groove 15 in the insulating sleeve 12 and the shoulder 14. The commutator segments are arranged on the insulating support with the segment portions 10 extending axially in the grooves 15 formed in the sleeve 12 and with the segment angular portions 11 arranged in the grooves 15 in the shoulder 14. A clamping ring 18 of insulating material is arranged over the segment portions 10 and engages the outwardly extending segment angular portions 11 and biases them into engagement with the grooves 15 in the shoulder 14 to a position as indicated by the dotted lines in Fig. 5, thereby biasing the segment axial portions 10 firmly against the insulating support 12. The sleeve 18

is provided with a plurality of clamping fingers 19 which is formed with inturned ends 20 arranged over the outer edge of the shoulder 14 and between adjacent segment angular portions 11 in order to clamp the ring in position. The inturned ends 20 of the clamping fingers 19 are formed on a smaller diameter than the outer diameter of the shoulder 14, and in assembling the commutator, the ring 18 is snapped into position and the inturned ends of the fingers 19 are clamped over the outer edge of the shoulder 14 and retain the commutator in assembled relationship.

While I have illustrated and described a particular embodiment of my invention, modifications thereof will occur to those skilled in the art. I desire it to be understood, therefore, that my invention is not to be limited to the particular arrangement disclosed, and I intend in the appended claims to cover all modifications which do not depart from the spirit and scope of my invention.

What I claim as new and desire to secure by Letters Patent of the United States is:

1. A commutator including an insulating sleeve support, an insulating element on said support extending outwardly at an angle thereto, a plurality of commutator segments having a portion of each extending axially and substantially parallel to each other on said sleeve support in spaced apart relationship and a portion of each formed at an angle to said axial portion, and means including a clamping ring for securing said segment angular portions clamped at an outwardly extending angle against said angular insulating element for biasing said segment axial portions firmly against said sleeve support.

2. A commutator including an insulating support having a shoulder thereon extending outwardly at an angle, a plurality of commutator segments having a portion of each extending axially and substantially parallel to each other on said support in spaced apart relationship and a portion of each formed at an angle to said axial portion, and means including a clamping ring for securing said segments on said support with said segment angular portions clamped against said shoulder at an outwardly extending angle.

3. A commutator including an insulating support having a shoulder thereon extending outwardly at an angle, a plurality of commutator segments having a portion of each extending axially and substantially parallel to each other on said support in spaced apart relationship and

a portion of each formed prior to assembly at a greater angle to said axial portion than said angle of said shoulder on said support, and means including a clamping ring for securing said segment angular portions clamped against said shoulder for biasing said segment axial portions firmly against said support.

4. A commutator including an insulating sleeve support having a shoulder thereon extending outwardly at an angle, a plurality of grooves in said sleeve and shoulder, a plurality of commutator segments having a portion of each extending substantially axially in said sleeve grooves and a portion of each formed prior to assembly at a greater angle to said axially extending portion than said angle of said shoulder on said support, and means including a clamping ring for securing said segment angular portions clamped against said shoulder.

5. A commutator including an insulating sleeve support having a shoulder thereon extending outwardly at an angle, a plurality of spaced apart grooves in said sleeve and shoulder, a plurality of commutator segments having a portion of each extending axially in said grooves in said support and a portion of each formed prior to assembly at a greater angle to said axial portion than said angle of said shoulder on said support, and means for securing said segments on said support with said segment angular portions clamped against said shoulder and biased to substantially the same angle as said shoulder for biasing said segment axial portions firmly against said support.

6. A commutator including an insulating support having a shoulder thereon extending outwardly at an angle, a plurality of commutator segments having a portion of each extending axially and substantially parallel to each other on said support in spaced apart relationship and a portion of each formed prior to assembly at a greater angle to said axial portion than said angle of said shoulder on said support, and means including a clamping ring for securing said segments on said support with said segment angular portions clamped against said shoulder and biased to substantially the same angle to said axial portion as said shoulder relative to said support for biasing said segment axial portions firmly against said support.

7. A commutator including an insulating support having a shoulder thereon extending outwardly at an angle, a plurality of commutator segments having a portion of each extending axially and substantially parallel to each other on said support and a portion of each formed prior to assembly at a greater angle to said axial portion than said angle of said shoulder on said support, and means including a clamping ring provided with fingers arranged between said segment angular portions and clamped about said shoulder for securing said segments on said support with said segment angular portions clamped against said shoulder and biased to substantially the same angle to said axial portion as said shoulder relative to said support for biasing said segment axial portions firmly against said support.
